United States Patent Office

Des. 187,409
Patented Mar. 8, 1960

187,409

GRATE

Alfred S. McQueen, Johnson City, Tenn.
Application April 1, 1959, Serial No. 55,302

Term of patent 14 years

(Cl. D81—18)

Fig. 1

Fig. 2

Fig. 8

Figure 1 is a top isometric view of a grate embodying my new design;
Figure 2 is a bottom isometric view thereof;
Figure 3 is a side elevational view thereof;
Figure 4 is a top plan view thereof;
Figure 5 is a rear elevational view thereof;
Figure 6 is a front elevational view thereof;
Figure 7 is an enlarged fragmentary vertical sectional view taken along line 7—7 of Figure 1; and

Figure 8 is an enlarged fragmentary vertical sectional view taken along line 8—8 of Figure 1.

I claim:
The ornamental design for a grate, as shown.
